MOUNT FOR CONTAINERS

Samuel N. Leopold and Henry K. Powell, Chicago,
Ill., assignors to Morris Paper Mills, Chicago, Ill.,
a corporation of Illinois

Application June 4, 1931, Serial No. 542,109

4 Claims. (Cl. 229—5.5)

This invention relates to a mount adapted to fit on the upper end of a collapsible container, such as a paper ice cream can, made in accordance with the invention disclosed in our co-pending application, Serial No. 503,019.

The main objects of the invention are to provide a device for maintaining the open end of a paper or other collapsible container in the desired distended condition; to provide means for preventing turning or lifting of a paper ice cream can as an incident to scooping ice cream therefrom when the can is nearly empty; to provide a device which will not tend to melt the ice cream in the portion of the can with which the device is associated; to provide a device which will form a non-cutting and rigid end on the can, and which end will afford a convenient edge over which to scrape or drag an ice cream scoop to remove excess ice cream therefrom, and, in general, it is the object of the invention to provide a mount for facilitating the use of paper or like flexible bodied containers, especially when used for containing ice cream.

Other objects and advantages of the invention will be understood by reference to the following specification and accompanying drawing in which a mount embodying a preferred form of the invention is illustrated. A lifter for handling ice cream cans to which the mount herein involved is applied, is also illustrated.

In the drawing:

Fig. 1 is a plan;

Fig. 2 is a side elevation of a container to which our improved mount is applied, the mount and adjacent portion of the container being shown in section;

Fig. 3 is a perspective of a lifter designed for handling full ice cream cans of the type herein described; and

Figs. 4 and 5 are views similar to Figs. 1 and 2, respectively, but showing a modified form of mount.

Referring now to the drawing, a container, in this instance, an ice cream can, is illustrated as including a can body 6 which is of cylindrical form and made of paper or like flexible material. The bottom of the container may be of any suitable construction and is shown as including a metal reinforcing ring 7.

In our above mentioned co-pending application, we have described in detail the construction and some of the advantages of using containers of this kind for transporting and storing ice cream. In the practical use of containers of this type, it has been noted that in a few instances

the can body has a tendency to collapse at its upper end, i. e., to assume an egg or oval shape instead of its normal cylindrical shape. It has also been found that in a few instances, when the can is nearly empty, there is a tendency to 60 spin or lift the can from the well of the refrigerator in which the can is usually stored, when scooping ice cream therefrom. The tendency to spin or lift the can appears only when it becomes quite light upon being emptied. 65

In order to overcome the objectionable tendencies above noted, we have provided a mount, designated as an entirety by the reference numeral 8, this mount being preferably made of a stainless or non-rusting metal. The mount includes a collar 9 which fits around the outside of the upper marginal portion of the can body 6 in spaced relation thereto, as indicated at 10. For assuring uniform, or substantially uniform, spacing of the collar 9 around the entire circumference of the can body, inwardly extending ribs 11 may be provided. The ribs 11 are formed integral with the collar 9 and, as clearly shown in Figure 2, extend transversely thereof. By inspection of Figure 1, it will be seen that the ribs 11 divide the 80 space between the can body 6 and the collar 9 into a plurality of separated air pockets.

At the upper end of the collar 9, we provide an inwardly extending flange 12 which overlies and is adapted to be seated on the upper end 85 of the can body 6, as clearly shown in Figure 2. The inwardly extending flange 12 serves to position the collar about the upper end portion of the can body. A rim 13 depending from the inner edge of the flange 12 is also provided, this 90 rim 13 fitting inside of the can body. The collar 9, flange 12 and depending rim 13 co-operate to embrace the upper end portion of the can body and to hold the same in properly distended position. 95

The rim and flange portions 13 and 12, respectively, of the mount 8 are preferably so formed as to provide a smooth, non-cutting end surface, as clearly shown in Fig. 2. Such a smooth and non-cutting surface is obviously desirable in that it avoids any danger of scratching or cutting the hand or arm of a person scooping ice cream from the container and in that it provides a firm edge over which the ice cream scoop may be scraped to remove surplus 100 ice cream. The air chambers 10 provided between the collar 9 and can body are desirable in that they permit cold air to circulate between the collar 9 and can body so as to prevent the transmission of heat from the collar through the can 105 110

body to the ice cream when the collar is first placed on the can.

In Figure 3, we have illustrated a lifting device which includes a strip of channel iron bent to substantially the shape shown. The part designated 14 constitutes a handle and the part designated 15 is provided at its lower end with a pair of teeth 16 adapted to bite into the outside of the container body. The portion 17 is provided with a depending pointed element 18. The pointed element 18 is spaced from the part 15 sufficiently to permit the mount to pass therebetween. However, in some cases, it has been found that the spacing of the pointed element 18 from the part 15 of the lifter is insufficient to permit the lifter to be readily placed in proper operative position. Inasmuch as it is somewhat objectionable to attempt to displace all present lifters with others in which the spacing of the parts referred to is sufficient to permit the lifter to be used when our improved mount is in place, we provide some mounts with notches, such as indicated at 19 in Figure 4, and a cutaway or flattened portion 20. It will be understood that the notch 19 is formed by removing a portion of the rim 13 and that the recessed portion 20 is formed by removing a small amount of metal from the outside of the collar 9. By this means, the thickness of the mount is reduced sufficiently to receive a lifter, substantially as shown in Figure 5.

By reference to Figure 5, it will be apparent that our mount 8 facilitates the use of lifters of the type shown, inasmuch as the can is, in effect, provided with a rigid upper end portion which will withstand such strains as are incident to lifting the weight of an ice cream can, even when only partly full. It is, of course, to be understood that the mount 8 is normally to constitute a part of the equipment of vendors of ice cream, and that the mount will be placed on the container either before or after it is inserted in the refrigerator well in the customary manner. Containers of the class described herein are equipped with a cover formed of paper and metal. Under some circumstances, the lifter described is used by piercing the cover with the pointed lifter element 18 and engaging the outside of the can body with the prongs 16. However, when the metal and paper cover is removed and disposed of, it becomes more difficult to use the lifter because of the flexibility and danger of tearing the paper body of the can. Our improved mount obviously avoids all of these difficulties.

As stated above, we prefer to make the mount of suitable stainless or rustless metal or other material which will be quite firm and rigid so as to impart the desired rigidity to the upper end of the container. We also prefer to make the mount of some such material which will give the mount sufficient weight to hold the can to the bottom of the refrigerator well and thus prevent spinning or lifting of the can incident to scooping ice cream therefrom.

We are aware that changes may be made in the structure above described without departing from the spirit of our invention, the scope of which should be determined by reference to the following claims, the same being construed as broadly as possible consistent with the state of the art.

We claim as our invention:

1. In combination with a collapsible ice cream container of the class described, a relatively rigid end mount removably associated with the container and comprising a collar fitting outside of and around the upper marginal portion of the container body, a flange extending inwardly from the upper edge of said collar for seating on the upper end of the container body to position the collar thereon, and a rim depending from said flange and fitting inside of said container body, said collar, flange and rim co-operating to embrace and maintain the upper end portion of the container body in distended condition, said collar being of such size as to provide space between itself and the outside of the container body portion around which it fits, thereby permitting air to circulate between the collar and said container body portion, and inwardly projecting ribs extending transversely of and formed integral with said collar for maintaining said space around the entire circumference of the container body.

2. In combination with a collapsible ice cream container of the class described, a relatively rigid end mount removably associated with the container and comprising a collar fitting outside of and around the upper marginal portion of the container and provided with an inwardly extending flange at its upper end for seating on the upper end of the container to position the collar thereon, said mount being formed of material and of such size as to provide sufficient weight to resist spinning and lifting of the container incident to the scooping of ice cream therefrom when the container is nearly empty, and said inwardly extending flange being provided with a depending rim adapted to fit inside of the container, said collar, flange and rim co-operating to embrace the upper end portion of the container body to maintain the same in predetermined distended condition, said rim being provided with a notch and said collar having a part of reduced thickness opposite the notch, substantially as and for the purpose described.

3. A device for holding a light-weight container in relatively fixed position to facilitate the removal of material from the container, comprising a weighted collar adapted to removably fit around a portion of the container and having means for engaging the container to support the collar on the container, said collar having a plurality of inwardly projecting ribs adapted to engage the container to maintain the inside of the collar in predetermined spaced relation to the container.

4. A device for holding a light-weight container in relatively fixed position to facilitate the removal of viscous material from the container, comprising a weighted collar adapted to removably fit outside of and around the upper marginal portion of the container, said collar having an inwardly extending flange adapted to engage the upper end of the container to support the collar on the upper end of the container, said flange being notched so as to provide a portion of reduced overall thickness to facilitate the application of a lifter substantially as described.

SAMUEL N. LEOPOLD,
HENRY K. POWELL.
